UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

PANEL BOARD.

Application filed April 9, 1920. Serial No. 372,426.

To all whom it may concern:

Be it known that I, HENRY F. STARRETT, a citizen of the United States, residing at Chicago, in the county of Cook and State 5 of Illinois, have invented new and useful Improvements in Panel Boards, of which the following is a full, clear, concise, and exact description, reference being had to the accompanying drawing, forming a part of 10 this specification.

My invention relates to panel-boards, and it has particular relation to devices of the character designated wherein the board is so sectionalized that any desired capacity 15 may be accommodated therefrom, and moreover, so constructed that either a three-wire of a two-wire system may be connected thereto for supply purposes without substantially altering the standard construction 20 employed.

For a better understanding of my invention reference may be had to the accompanying drawings wherein:—

Fig. 1 is a front elevational view of a 25 panel-board constructed in accordance with my invention and adapted for connection to the three-wire supply system;

Fig. 2 is a rear elevational view of the 30 board shown in Fig. 1;

Fig. 3 is a front elevational view of one 35 section of the panel-board;

Fig. 4 is an enlarged elevational view of a portion of the board showing one of the receptacles thereon, as well as the switching 40 means which is utilized to connect the receptacle to a panel-board bus bar;

Fig. 5 is a sectional elevational view taken on the line 5—5 of Fig. 4 and illustrates in detail a particular type of switch which I 45 have found to be utilitarian in installations of this character; and

Fig. 6 is an elevational view of a panel-board embodying my invention illustrating the manner in which the bus bars are connected when a two-wire system is utilized 50 as a source of supply.

In the panel-board art, particularly in connection with panel-boards which are used intermediate a main source of supply and 55 a plurality of branch circuits, and which embody bus bars, fuse receptacles, and con-

necting means between the latter two elements, it is desirable that the panel-board have a high degree of flexibility. One object of my invention, therefore, is to provide a simple and improved construction 60 of sectionalized panel-board wherein the number of sections may be increased as desired without reconstruction and reorganization of the board as a whole.

Another object of my invention is to provide a panel-board which is composed of a number of base sections wherein the bus bars are so arranged on the component base sections of the board that either a three-wire 65 system of supply or a two-wire system of supply may be connected thereto, and in this particular relation I find that the specific panel-board sections, which are hereinafter illustrated, are particularly adapted to the 70 attainment of the desired end.

Finally the third object of my invention is to provide a panel-board wherein the connections between the branch-line circuits and the main circuits are through protective 75 devices or terminals and wherein the connection between the main leads and the branch-lines are easily broken in the individual branches by means of a single pole switch. In this relation I find that the 80 switch hereinafter illustrated lends itself particularly well to a construction which may be utilized on the panel-board and occupy a minimum of space thereupon by reason of a particular feature of its construction, hereinafter described.

In view of the fact that the use of a switch in but one side of a branch line circuit is now permitted, I find that a panel-board constructed, as above intimated, results in a 90 considerable space economy. Inasmuch as it is no longer necessary to provide switches associated with the return sides of the branch circuits, the fuses therein may be mounted upon one base section, and the latter so aligned in transverse relation with the other sections of the panel-board that the space, which would otherwise be wasted if the last named fuses were mounted in the same manner as the fuses in the outgoing 95 branch circuits, is utilized. The manner in which this is accomplished will appear in 100

the hereinafter detailed description of my improved panel-board.

Referring now more particularly to the drawings, a panel-board comprising upright 5 retaining members 1 and 2, to which are secured panel-board base sections 3, 3^a, 4 and 5, is shown. The sections 3 and 4 may be hereinafter termed receptacle or terminal sections while the section 5, having mounted 10 thereupon a switching means 6, may be designated as a main switch panel.

Mounted upon the base section 4 are a plurality of receptacles 7—7 of any conventional type and it will be observed that 15 branch-line circuits may be attached to binding posts 8—8 and thus connected to the receptacles 7. Associated with the base section 4 are bus bars 9, 10 and 11, the buses 9 and 11 being, for purpose of illustration, 20 regarded as adapted for connection to the positive and negative lead wires of a three-wire supply system, while the bus 10 may be connected through the switching means 6 to the neutral wire of said three-wire system. 25 The receptacles 7 are, of course, in the illustrated form, provided with center contacts 12—12, which are connected by means of switches 13—13 to the positive and negative buses 9 and 11.

30 Abutting the upper end of the base section 4 is the base section 3^a upon which are mounted additional receptacles 14 connected, as shown, directly to transverse bus bar 15. It will be noticed that the last described receptacles 14 and the bus bar 15 are arranged 35 transversely with respect to the receptacles 7—7 and the busses 9, 10 and 11. The bus 15 is connected to an auxiliary bus bar 15^a which latter is adapted to be connected to 40 a corresponding bus on another transverse section and to the bus 10 and it is apparent, therefore, that the receptacles 14 may, through the intermediary of binding posts 45 16, be connected to the other side of the branch-line circuits, it being assumed that the branch circuits each requires a potential impressed thereacross equal to the potential existing between either the positive or the negative supply lead and the neutral supply lead.

50 To illustrate the degree of flexibility which may be attained I show other more neutral branch-line receptacles positioned on the second individual base section 3. 55 This section is provided with receptacles 17 which are directly connected to a bus bar 18 and which are provided with appropriate binding posts 19 adapted for connection to the return leads of the branch-line circuits. 60 An auxiliary bus bar 20 is provided on the section 3, is connected to the bus bar 18, and so extends over the edge of the base section 3 and under the edge of the base section 4 that connection may be made between the 65 buses 10, 15^a and 18, whereby the last-named

bar comprises a portion of the neutral bus bar system.

The base sections may, of course, be arranged in different order from that illustrated in Figure 1, since the section 3 and 70 all other sections which may be added to the board are so formed that they may be added to either end thereof. Moreover, any number of sections, as illustrated at 4, may be added to the board when an increased 75 capacity is desired.

The arrangement shown, results in all of the branch-line-return circuits being positioned at the top of the panel-board and, moreover, admits of a simple and compact 80 arrangement of the outgoing lines in one section of the board, features which are desirable in an apparatus of this character. Moreover, all of the sections, as above intimated, may be made of standardized construction and may, therefore, be installed 85 with little effort.

The advantage of such a construction may be realized from the following considerations. Under the present underwriter's rules, the insertion of a switch in both lines of a branch circuit derived from a panel-board is not necessary, and I have, therefore, placed a switch in the outgoing lines only, as shown. If now the return 90 line receptacles are disposed on a base section in the same manner as those in the outgoing lines, the space which has heretofore been occupied by the switches would be wasted. I therefore, provide a more compact arrangement and eliminate this wasted space by mounting the return line receptacles transversely with respect to the outgoing line receptacles on a separate base section. In this manner substantially twice 100 105 as many return-line receptacles are accommodated as have been heretofore in a like space.

In Figure 2, wherein the rear of the panel-board is illustrated, it will be noted that the 110 bus bar 10 which was assumed as a neutral bus is mounted upon the rear face of the board. In this manner the three bus bars may be carried by the board and a maximum insulation maintained therebetween, although the minimum space is occupied. This figure also illustrates in detail the manner in which the various sections are secured to the retaining members 1 and 2.

Fig. 3 illustrates a standard base section 120 such as those shown at 3 and 3^a, which may be added to the board to increase the number of branch-line circuits which may be accommodated thereupon.

The particular switching means which I 125 find it desirable to employ, when minimum space requirements are to be satisfied, is illustrated in Figs. 4 and 5. The switch 13 comprises a hinged conducting member 21 adapted for rotation about the lug 22 which 130

is connected to one side of the receptacle 7. The member 21 is adapted to be received in a clip 23 and may be forced thereinto by an insulating handle portion 24 mounted thereupon. The handle 24 is provided with concave sides 25—25. This particular type of handle and small switch construction is beneficial when used on the panel-board because of the minimum space required thereby, and especially because of the ease with which the handle 24 may be grasped to open the switch 13.

It will be noted that each receptacle has associated therewith a raised window-like portion 27, which is adapted to receive and exhibit a designating symbol whereby the circuits derived from the panel-board may be identified.

In Fig. 6 I have illustrated a panel-board 20 having substantially the same characteristics as that illustrated in Fig. 1. In this instance, however, the board is assumed to be used with the two-wire circuit, and, therefore, the branch circuits are impressed with 25 the full potential existing between the positive and negative sides of the supply system. The main switching means in this embodiment of my invention consists, of course, of a double pole switch. The sectionalizing is, however, utilized in the same manner as was described in connection with Fig. 1 by connecting together the two outside bus bars on the section 4, and utilizing the bus bar 10 as the positive or negative 35 side of the supply system as desired. Moreover, I have shown in this figure, clip retained fuses rather than the plug fuses illustrated in Fig. 1.

As will be observed from the foregoing 40 description I have provided a panel-board wherefrom any desired number of branch-line circuits, within certain limits, may be supplied and wherein the various base sections are so constructed that any number thereof may be simply embodied in the board. Moreover, it will be observed that 45 by aligning the bus bars and the associated receptacles on the various base sections as described, the change from a three-wire to a two-wire panel-board may be effected by 50 a comparatively simple change in the bus bar construction and the subsequent connection to the receptacle base sections of an appropriate pole number switching base 55 section.

While I have described but two embodiments of my invention it is apparent that many modifications therein may occur to those skilled in the art, and I desire, therefore, that the invention be limited only by the showing of the prior art or by the scope 60 of the appended claims.

Having thus described my invention, what I claim as new and desire to secure by Letters Patent is:

1. In a panel-board, a base section embodying receptacles and having buses mounted thereupon, another base section, embodying receptacles and having a bus mounted thereupon, adapted for aligned association with said first base, the receptacles on said first-named base being adapted for connection to some of its said buses, and all those on second-named base section being adapted for connection only to the other 75 bus on said first mentioned base section.

2. In a panel-board, a base having buses mounted thereupon, another base adapted for aligned association with said first base and having a bus mounted thereupon, and 80 means for exclusively connecting one of the buses on said first-named base to the bus on said last-named base.

3. In a panel-board, a base having receptacles associated therewith and having buses mounted thereon, means for connecting some of said receptacles to one of said buses and means for connecting others of said receptacles to another of said buses, another base having a bus mounted thereupon arranged 90 in alignment with said first-named base, and means for exclusively connecting one of said buses on said first-named base with the bus on said last-named bus.

4. In a panel-board, individual base members provided with terminals and having buses mounted thereupon, means for connecting some of the terminals to the bus adjacent thereto, respectively, and means for exclusively connecting the other buses to 100 all of the other terminals.

5. In a panel-board, a base having terminals thereupon arranged on either side of a medial line thereof, buses mounted upon said base, another base adapted for aligned association with said first-named base and having terminals mounted thereupon, one bus upon said last-named base to which all the terminals thereupon are connected, and means for connecting said last-named bus 110 to one of the busses upon said first-named base.

6. In a panel-board, a base having receptacles thereupon and having receptacles arranged on either side of a medial line thereof, buses mounted upon said base member, another base adapted for aligned association with said first-named base and having receptacles mounted thereupon, a bus upon said last-named base to which the receptacles 120 thereupon are connected, and means for connecting said last-named bus to one of the busses upon said first-named base, the receptacles on said last-named base member being aligned transversely with respect to the receptacles on the first-named base member.

7. In a panel-board, a base member provided with branch-line terminals, buses mounted upon said base, means for connecting certain of said buses to said branch line 130

- terminals, a second base section adapted for alignment with said first-named base and having terminals mounted thereupon in transverse alignment with the terminals connected to the aforementioned buses, and means for connecting the other bus on said first-named base to the bus on said last-named base. 5
8. In a panel-board, a base member provided with branch-line receptacles, buses mounted upon said base, means for connecting said buses to said branch-line receptacles comprising single throw switches, a second base section adapted for alignment with said first-named base and having receptacles mounted thereupon in transverse alignment with the receptacles connected to the aforementioned buses, and means for connecting the other bus on said first-named base to the bus on said last-named base. 10
9. In a panel-board, a base member provided with branch-line receptacles, buses mounted upon said base, means comprising switches provided with a handle portion having concave re-entrant portions thereupon for connecting said buses to said branch-line receptacles, a second base section adapted for alignment with said first-named base and having receptacles mounted thereupon in transverse alignment with the receptacles connected to the aforementioned buses, and means for connecting the other bus on said first-named base to the bus on said last-named base. 15
10. A panel-board, comprising a plurality of base sections, bus bars on said sections adapted for connection to a source of supply, terminals on said base members, means whereby one of said bus members may be connected to a transversely extending bus member on another base section, said last named base section being mounted adjacent to and in alignment with said first-named base section, branch-line terminals on each of said base sections, the terminals on said first-named base member being adapted for connection to two of said bus members and other branch-line terminals mounted on said second-named base member and being adapted for connection to said transversely extending bus member. 20
11. In a panel-board, an insulating base section having a plurality of branch-line receptacles mounted thereupon on either side of a medial line thereof, a plurality of buses mounted substantially parallel to said medial line, means comprising single throw switches for connecting said receptacles to the immediately adjacent bus, another bus mounted transversely to said other buses on said base section, means for connecting said bus to one of said first-named buses, means for connecting to said transverse bus the receptacles adjacent thereto, another base section adapted for alignment with said first- 25
- named base section and having a bus mounted thereupon, branch-line receptacles on said second-base section, and means for connecting said second-base section bus to one of said first-base-section buses. 70
12. In a panel-board, an insulating base section having a plurality of branch-line receptacles mounted thereupon on either side of a medial line thereof, a plurality of buses mounted substantially parallel to said medial line, two of said buses being mounted on the receptacle face of said base and another of said buses being mounted on the other face thereof, means for connecting the first two buses to said receptacles, another base section aligned with said first section and having receptacles and a bus to which said receptacles may be connected mounted thereupon, and means for connecting said last-named bus to said second-named bus on said first-named base section, whereby any desired number of base sections may be embodied in said panel as dictated by the capacity thereof. 75
13. In the panel-board art, a panel-board comprising a plurality of basic units, circuit controlling equipments mounted on said units for exclusive insertion in series into one line of each branch circuit connected to said panel-board, a second plurality of basic units, circuit controlling equipments mounted on said second set of units for exclusive insertion in series in the other line of each one of said branch circuits connected to said panel-board, and means for securing all of said units in an aligned built-up panel-board. 80
14. In the panel-board art, a panel-board comprising a basic unit, circuit controlling equipments mounted adjacent the lateral edges of said unit for exclusive insertion in series into one line of the branch circuit to be connected to said unit, a plurality of units having a length substantially equal to the width of the basic unit, circuit controlling apparatus mounted on said plurality of units for exclusive insertion in series in the other line of said branch circuit, and means for securing all of said units in an aligned built-up panel-board. 85
15. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 90
16. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 95
17. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 100
18. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 105
19. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 110
20. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 115
21. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 120
22. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 125
23. In the panel-board art, a panel-board comprising a basic panel unit, fuses and single throw switches mounted on same, said fuses and switches being disposed in substantially paralleling columns on either side of said unit and connected in series to one side of the branch circuit connected to said unit, a second basic unit, a plurality of fuse receptacles mounted on said unit, said fuse receptacles being adapted to be connected to the other lines of the branch circuits which are to be connected to said panel-board, said fuse receptacles being disposed at substantially right angles to the fuses and fuse receptacles of the first unit, the switches on 130

said first unit serving to act as the sole switch controlling element on the panel-board for said branch circuits.

16. In the panel-board art, a panel-board comprising a plurality of basic units, circuit controlling equipments mounted on said units for insertion in series in one line of each branch circuit connected to said panel-board, a second plurality of basic units, cir-

cuit controlling equipment mounted on said 10 second set of units at substantially right angles to the circuit controlling equipment of said first plurality of units, and means for securing all the units in an aligned, built-up panel-board.

15 In witness whereof, I have hereunto subscribed my name.

HENRY F. STARRETT.
